(57) **CLAIM**

The ornamental design for a mobile phone with a graphical user interface, as shown and described.

DESCRIPTION

FIG. 1 is a front view of a mobile phone with a graphical user interface showing a first embodiment of our new design; FIG. 2 is a rear view of the first embodiment; FIG. 3 is a left side view of the first embodiment, the right side view being a mirror image of the left side view; FIG. 4 is a top view of the first embodiment, the bottom view being a mirror image of the top view; FIG. 5 is a front view of a mobile phone with a graphical user interface showing a second embodiment of our new design; FIG. 6 is a rear view of the second embodiment; FIG. 7 is a left side view of the second embodiment, the right side view being a mirror image of the left side view; FIG. 8 is a top view of the second embodiment, the bottom view being a mirror image of the top view; FIG. 9 is a front view of a mobile phone with a graphical user interface showing a third embodiment of our new design; FIG. 10 is a rear view of the third embodiment; FIG. 11 is a left side view of the third embodiment, the right side view being a mirror image of the left side view; and, FIG. 12 is a top view of the third embodiment, the bottom view being a mirror image of the top view.

The broken line drawings of the mobile phone in all the views and portions of the graphical user interface in FIGS. 1, 5, and 9 are included for the purpose of illustrating environmental structure and portions of the mobile phone with graphical user interface and form no part of the claimed design.

1 Claim, 12 Drawing Sheets
